WINDOW CONSTRUCTION FOR CONVERT-
IBLE BODIES

Jules A. Olivier, Grosse Pointe Farms, Mich., as-
signor to The Murray Corporation of America,
Detroit, Mich., a corporation of Delaware

Application May 4, 1938, Serial No. 205,874

2 Claims. (Cl. 296—44)

The present invention relates to vehicle window constructions and in particular, provides an improved window construction characterized as having two glass sections disposed in laterally offset planes so that one thereof can be swung to a lowered position relative to the other.

Principal objects of the present invention are to provide an improved window construction of the above generally indicated type, which is simple in construction, may be readily manufactured and assembled, and which is efficient in operation; to provide such a construction embodying improved operating mechanism for the individual window sections; to provide such a construction characterized in that one of the glass sections is vertically slidable relative to the door and the other of the sections is rotatable between raised and lowered positions; and to provide such a construction which is particularly applicable, but is not limited, to bodies of the so-called convertible type.

With the above, as well as other objects in view, which appear in the following description and in the appended claims, a preferred but illustrative embodiment of the invention is shown in the accompanying drawing, throughout the several views of which corresponding reference characters are used to designate corresponding parts and in which:

Figure 1 is a view in outside elevation, with certain of the parts broken away, of a vehicle door embodying the improvements of the present invention, and showing the glass sections in raised positions;

Figure 2 is a detailed sectional view, taken along the line 2—2 of Figure 1;

Figure 3 is a view in vertical transverse section, taken along the line 3—3 of Figure 1, but showing the glass sections in lowered positions;

Figure 4 is a top view, showing the offset relation between the individual glass sections; and

Figure 5 is a detailed view in vertical section, taken along the line 5—5 of Figure 3.

Referring to the drawing, the present invention is herein illustrated as being specifically applied to a rear door for a vehicle of the so-called convertible body type. It will be understood, however, that the improvements of the present invention are equally applicable to both front and rear doors and that the improvements are correspondingly applicable to doors intended for use in bodies of the closed type.

The illustrated door comprises a lower, preferably metallic, body portion 10, having an outer panel 12 and an inner panel 14 which are con-

ventionally secured together, and which, except where the context otherwise requires, may be and preferably are of conventional construction forming a door well. In accordance with the present invention, the door is provided with two glass sections 16 and 18, the glass section 16 being vertically slidable from the raised position shown in full lines in Figure 1 to the lowered position shown in dotted lines in such figure. The 5 companion and smaller glass section 18 is rotatable from the raised position shown in full lines in Figure 1 to the lowered or retracted dotted line position shown in the same figure. As clearly appears in Figures 2, 3, and 4, sections 16 and 18 are disposed in laterally offset planes relative to each other, so that section 16 may be raised and lowered independently of adjacent section 18, and so that the section 18 may be swung between its raised and lowered positions 10 independently of the position of the section 16. Preferably, and as illustrated, the smaller section 18 is positioned inwardly of the larger section 16.

The larger glass section 16 is provided with 25 the usual frame 20 of channel shape, which extends completely therearound, and a corresponding channel shaped frame 22 is provided for the smaller glass section 18. The frame element 22 is reversely bent along its forward edge, as indicated at 24 in Figure 2, so as to provide a channel to receive a sealing strip 26. The sealing strip 26 extends from the bottom to the top of the smaller glass section 18, and forms a continuous seal between the adjacent edges of the 30 two window sections.

The larger window section 16 is supported within the associated door 10 by means of a pair of spaced vertically disposed channel members 28 and 30. The channels 28 and 30 may be 35 suitably and conventionally supported within the body portion of the door, as will be understood. The channel 28 is dimensioned to relatively freely slidably but snugly receive the front portion of the frame 20 of the section 16, so as to support and guide such portion of the window frame during the upward and downward movements of the latter.

The channel 30 at the rear edge of the larger window section 16, is suitably supported within 40 the body portion of the door, and is formed to cooperate and form a rolling guide for a pair of rollers 32 and 34, which are rotatably journaled upon a bracket 36 which is secured to and extends downwardly from the lower rear corner of 45 the window section 16. The rollers 32 and 34

are spaced sufficiently apart vertically of the door so as to afford a firm support to the section 16 against tilting movement of the latter.

The operating mechanism for the window section 16 is illustrated as comprising a pair of arms 38 and 40, which are rotatably journaled upon trunnions 42 and 44 which are in turn supported from a bracket or plate 46 which is secured within the body of the door in any suitable way. The ends of the arms 38 and 40 are provided with rollers 46 and 48, respectively, having grooved peripheries, which ride between track elements 52 and 54 which are formed at the lower edge of the section 16. The track element 52 is illustrated in Figure 3 as being formed integrally with the lower frame portion 20 for the glass section 16. The companion track element 54 is illustrated as being formed in a depending bracket 56 which is secured to the outer face of the frame 20.

The trunnions 42 and 44 also carry gear segments 58 and 60 which are non-rotatable relative to the arms 38 and 40, respectively. The gear segments 58 and 60 are rotatable in response to rotation of a conventional handle 62 through intermediate gears 64, 66, 68, and 70 and a gear segment 72. With this relation, it will be appreciated that rotation of the handle 62 in a window lowering direction causes the arms 38 and 40 to rotate in clockwise and counter-clockwise directions, respectively, about the trunnions 42 and 44, which action lowers the window section 16 through the cooperation between the rollers 46 and 48 with the previously mentioned guide elements 52 and 54. The lowering movement moves the arms 38 and 40 from the raised position indicated at *a* to the fully lowered position indicated at *b*, in which position the window section 16 is fully withdrawn into the body of the door.

The companion window section 18 is supported within the door by means of a trunnion 70, the opposite ends of which are supported in the door body, and an arcuately formed channel-shaped guide element 72, which receives a roller 74 carried upon a bracket 76 which depends from the lower edge of the frame of the window 18. The window section 18 is connected to the trunnion 70 through a casting or equivalent bracket 78. The arcuately shaped channel guide 72, in section, preferably corresponds to the structure of the previously described channel guide 30 associated with the window 16, and cooperates in a similar manner with the roller 74.

The regulating mechanism for the smaller window section 18 comprises an arm 82, which

rides in an elongated slot 84 formed in a bracket 86 which depends from the lower edge of the window 18. The arm 82 is provided with a roller or its equivalent which is received within the slot 84. The arm is disposed for rotation in response to movements of the handle 88, through a train of gears including gears 90 and 92. The gears 90 and 92 are rotatably supported upon a plate 94 which is suitably supported within the body 10 of the door. In operation, it will be appreciated that rotation of the handle 88 in a window lowering direction causes rotation of the arm 82 in a clockwise direction. This rotation of the arm 82, through its cooperation with the slotted bracket 86, forces the window 18 to rotate in a counterclockwise direction around its supporting trunnion 70. The parts are so adjusted that the rotation of the window 18 can be continued until it is completely concealed within the body of the door, as is indicated in the dotted line showing 15 thereof in Figure 1.

From the foregoing, it will be appreciated that the present invention provides an extremely efficient and satisfactory window construction, embodying an improved relationship of the respective glass sections of the window so as to permit independent retracting movements thereof and also embodying improved supporting and regulating mechanism for the individual window sections.

Although only a specific embodiment of the invention has been described in detail, it will be appreciated that various changes in the form, number, and arrangement of parts thereof may be made within the spirit and scope of the invention.

What is claimed is:

1. In a window construction in a door having a well, the combination of a vertically slidable window section for enclosing a part only of the space above the well, a second window section, and means supporting said window sections within said well in laterally offset relation to each other so as to permit independent movement 40 thereof into said well.

2. In a window construction, the combination of a slidable window section, a second window section pivotally mounted for movement in a plane parallel to said first section, said window sections being supported in laterally offset relation and each enclosing a portion only of the window opening, and a sealing element carried by one of said sections and disposed to abut the other section so as to form a seal between said 50 two sections.

JULES A. OLIVIER.
